UNITED STATES PATENT OFFICE

WALTER D. TEAGUE, OF FOREST HILLS, NEW YORK, ASSIGNOR TO BAUSCH & LOMB
OPTICAL COMPANY, OF ROCHESTER, NEW YORK, A CORPORATION OF NEW YORK

DESIGN FOR A READING GLASS

Application filed October 22, 1931. Serial No. 41,485. Term of patent 7 years.

To all whom it may concern:

Be it known that I, WALTER D. TEAGUE, a citizen of the United States, and a resident of Forest Hills, county of Queens and State of New York, have invented a new, original, and ornamental Design for a Reading Glass, of which the following is a specification, reference being had to the accompanying drawing, forming a part hereof.

Fig. 1 is a front and rear view of a reading glass embodying my new design.

Fig. 2 is an edge view of same.

Fig. 3 is a sectional view taken on line 3—3 of Fig. 1.

I claim:

The ornamental design for a reading glass, substantially as shown.

WALTER D. TEAGUE.
